UNITED STATES PATENT OFFICE.

HENRY J. KIMMEL, OF PITTSBURGH, PENNSYLVANIA.

DESIGN FOR A MILK-BOTTLE HOLDER.

53,853.

Specification for Design.

Patented Sept. 16, 19

Application filed July 10, 1918. Serial No. 244,330. Term of patent 14 years.

To all whom it may concern:

Be it known that I, HENRY J. KIMMEL, a citizen of the United States, residing at Pittsburgh, Allegheny county, Pennsylvania, have invented a new, original, and ornamental Design for a Milk-Bottle Holder, of which the following is a specification, reference being had to the accompanying drawing, forming a part thereof.

The figure is a perspective view of a milk-

bottle holder showing my new and ornamental design.

I claim:

The ornamental design for a milk-bottle holder as shown.

HENRY J. KIMMEL.

Witnesses:

THOMAS HANBURY,
AUSTIN LEE GEORGE.
